C. M. VAN HEUSEN,
CHIME ATTACHMENT FOR TELEPHONE SIGNAL BOXES,
APPLICATION FILED MAY 27, 1918.

1,307,467.

Patented June 24, 1919.

Inventor
Charles M. van Heusen
By his Attorneys
Lannie Atwell Marvin Edmunds

UNITED STATES PATENT OFFICE.

CHARLES MANNING VAN HEUSEN, OF ALBANY, NEW YORK.

CHIME ATTACHMENT FOR TELEPHONE SIGNAL-BOXES.

1,307,467.

Specification of Letters Patent. Patented June 24, 1919.

Application filed May 27, 1918. Serial No. 238,716.

To all whom it may concern:

Be it known that I, CHARLES M. VAN HEUSEN, a citizen of the United States, residing at Albany, in the county of Albany, 5 State of New York, have invented certain new and useful Improvements in Chime Attachments for Telephone Signal-Boxes; and I do hereby declare the following to be a full, clear, and exact description of the invention, such as will enable others skilled 10 in the art to which it appertains to make and use the same.

This invention, like the one disclosed in my application filed concurrently herewith, 15 is directed to the production of an attachment for the signal boxes employed in connection with telephone call bell systems, the attachment being adapted to be substituted for the usual hammer and gongs of such 20 bells, to produce a vibrating sound of pleasing pitch and timbre, capable of variation in tone and effect, instead of the harsh sound heretofore produced with a view solely to giving an alarm.

25 The usual telephone call box is one inclosing an electromagnet and having an opening in the top through which the stem of a vibratory hammer projects, and also having gong posts projecting upwardly 30 from the top on opposite sides of the hammer and adapted to support gongs. The vibration of the hammer causes it to strike the two gongs alternately, but the sound emitted 35 is a harsh, strident and unmusical sound which is disagreeable and unnecessarily startling.

The present invention is directed to the 40 production of an attachment for such a call box, specially constructed so as to facilitate mounting it in position without disturbing or altering the parts of the signal box other than by the removal of the gongs, whereby 45 pleasing musical sounds, equally effective as signals, will be substituted for the strident and unmusical sounds of the ordinary alarm.

50 The attachment whereby this end is accomplished consists of a striker adapted to be securely mounted upon the end of a hammer of the telephone signal box, without requiring any change in the hammer or affecting its vibratory movement, a frame extending upwardly from the gong posts and detachably fastened thereto, and one or more elongated bells suspended from the frame in co- 55 operation with the striker, means being provided for adjusting the bell toward and

away from the striker. Preferably the bell is fastened to the frame in adjusted position relatively to the striker, and the frame may be fastened to the gong posts of the telephone box in adjusted position. In this way provision is made for adjustment of the signal apparatus to permit of the minute regulation seemingly required for the effect desired under the particular conditions existing in almost every individual case. So, 60 also, the striking surfaces of the striker are padded or otherwise constructed to eliminate or reduce the metallic sound so common in telephone signal apparatus as at present constructed. The bells are preferably elongated tubes of glass or a bell metal having a pleasing tone, and where two are provided on opposite sides of the striker, they may be of different lengths to simulate chimes. 65

In the preferred construction hereinafter described, a resilient rod is fastened at one end to the bell and terminates at the other end in a ball weight, whereby when the bell is vibrated by impact with the striker, the 70 rod is also set into vibration and results in the production of a waving sound or crescendo effect. 75

These devices may have various forms in accordance with my invention, as appears in 80 the accompanying drawings, in which,

Figure 1 is an elevation, partly in section, of the preferred form of the invention; Fig. 2 is a section on line 2—2 of Fig. 1; Fig. 3 is an elevation partly in section, showing a 90 modified form of the frame; Fig. 4 is a perspective view of a yoke for supporting the bell; Fig. 5 is a perspective view of a further modified form of frame; Fig. 6 is a perspective view of the lower portion of still 95 another form of frame; and Fig. 7 is a perspective view of a frame wherein a single bell may be adjusted in position both vertically and laterally toward and away from the striker. 100

In all of the embodiments of the invention illustrated in the drawings, the usual form of telephone box is shown at 1. This box has an opening in the top through which projects the hammer 2 which is adapted to be vibrated rapidly by an electromagnet located within the box. On opposite sides of the vibratory hammer are posts 3 mounted stationarily upon the top of the box and projecting upwardly therefrom. The upper 105 ends of the posts 3 have threaded openings in them, and in the ordinary form of signal

box the gongs are mounted on these posts on opposite sides of the hammer by screws entering the threaded openings in the posts.

The attachments constituting the present invention consist of a striker 4 secured to the ball end of the hammer 2, and one or more elongated chime bells, such as tubes of glass or of bell metal of pleasing sound. The striker may be adjustable toward or away from the bell or bells, as is more fully described in my copending application herein referred to, although, in this application, I show a divided striker 4, the parts of which are adapted to be screwed together into clamping engagement with the ball end of the hammer, and to be held in clamped position by a locking screw. The striking surfaces or surfaces of the striker are covered with leather, ebony, ivory, cork, or other material to eliminate or reduce the metallic sound upon impact with the bells.

The bell or bells are suspended from a frame extending above the gong posts 3, and fastened thereto in any suitable way. In all cases shown herein the bells are adjustable in minute increments toward and away from the striker by laterally adjusting the bells in position in the frame, or by adjusting the frame in relation to the gong posts, or both.

In Fig. 1 the frame 5 consists of a flat metal strip perforated and bent into a partly closed rectangular form. The feet 6 have elongated slots 7 through which extend the posts 3 of the usual form of telephone signal box, thereby providing lateral adjustment. The frame is secured in adjusted lateral position by means of caps 8, which are screwed on the posts 3. The two bells 9 and 10 are tube-shaped and of different lengths to simulate chimes. Each is suspended from the frame by means of a yoke 11 which, as shown best in Fig. 4, has seats 12 for the laterally extending posts 13, and pivoted latches 14 arranged to rigidly hold the posts

45 to their seats. Felt washers 15 around the posts 13 between the yoke and bell, and rubber coverings 16 surrounding the posts, prevent any substantial suppression or damping by the support of the vibration of the bell.

50 The yoke is fastened in adjusted position in an elongated slot 18 of the upper cross-bar 19 of the frame by means of the screw-threaded rod 20 and the nuts 21, this arrangement permitting a limited vertical adjustment of the yoke as well as a lateral adjustment thereof. As shown best in Fig. 2, a rod is fastened to the crown of the bell and has a resilient portion 22 terminating in a weight 23 so that the rod and weight are set

55 into vibration by the vibration of the bell and thereby produce a waving sound or crescendo effect.

The construction of the embodiment shown in Fig. 3 is similar to that of Fig. 1 in many respects. The principal difference

is that the frame 24 is not adjustable relatively to the gong posts 3, but terminates in caps 25 adapted to set over the gong posts and to be fastened thereto by screws 26.

In Fig. 5, the frame 27 has feet 28 with open-ended slots 29 and a continuous slot 30 in the cross-bar 31 to provide more lateral adjustment than in the embodiments of Figs. 1 and 2.

In Fig. 6, the frame 32 is provided with feet 33, each having a hole 34 adapted to set snugly over a gong post and to be secured thereto by a cap or other suitable means.

The frame 35 shown in Fig. 7 is adapted for supporting a single bell. It has a vertical slot 36 whereby the bracket 37 may be fastened to the frame in vertically adjusted position. This bracket has an elongated slot 38 for lateral adjustment of the bell toward and away from the striker.

In the drawings, various constructions are illustrated in which the parts constituting the attachment of the present invention may be embodied, and it will be understood that other constructions different from those illustrated may be employed if desired. In all cases, however, it will be noted that the attachment consists of a striker adapted to be attached to the ball hammer of the telephone signal box without requiring any change or substitution therein, and a laterally adjustable bell or bells coöperating with the striker and suspended in position from a support arranged to be secured to the stationary threaded posts of the telephone box. The frame may be laterally adjustable relatively to the gong posts, and the bell or bells may be vertically adjustable relatively to the striker. In all of these various forms of construction, the adjustment provided permits regulation of the bell or bells toward and away from the striker in minute increments to regulate the sound produced as may be found desirable.

Having described my invention, what I claim is:

1. An attachment for a telephone signal box having a gong post mounted on its top and a vibratory hammer, said attachment comprising a striker adapted to be secured to the hammer, a frame adapted to extend vertically above the gong post and including an elevated cross-piece, an elongated sounding device for coöperation with the striker suspended axially from the cross-piece, and means whereby the sounding device may be adjusted bodily in a direction transverse to its axis toward and away from the striker; substantially as described.

2. An attachment for a telephone signal box having a gong post mounted on its top and a vibratory hammer, said attachment comprising a striker adapted to be secured to the hammer, a frame adapted to extend vertically above the gong post and includ-

- ing an elevated cross-piece, and an elongated sounding device for coöperation with the striker suspended axially from the cross-piece and adjustable bodily in the frame and 5 relatively to said cross-piece in a direction transverse to its axis toward and away from the striker; substantially as described.
3. An attachment for a telephone signal box having the usual gong posts mounted on its top and the usual vibratory hammer, 10 said attachment comprising a striker adapted to be secured to the hammer, a frame adapted to extend vertically above the gong posts and including an elevated cross-piece, 15 and an elongated sounding device for coöperation with the striker suspended axially from the cross-piece, the frame being adapted for adjustable connection to at least one of the gong posts for movement laterally 20 toward and away from the striker; substantially as described.
4. An attachment for a telephone signal box having the usual gong posts mounted on its top and the usual vibratory hammer, 25 said attachment comprising a striker adapted to be secured to the hammer, a frame adapted to extend vertically above the gong posts and including an elevated cross-piece, 30 and an elongated sounding device for coöperation with the striker suspended axially from the cross-piece, the frame being adapted for adjustable connection to at least one of the gong posts for movement laterally 35 toward and away from the striker, and the sounding device being independently adjustable within the frame and relatively to the latter and its cross-piece toward and away from said hammer; substantially as described.
- 40 5. An attachment for a telephone signal box, said attachment comprising a frame adapted to extend above the usual gong posts of the box, a hollow bell suspended from the frame, a striker adapted to be secured to the usual hammer of the box in position to impact against the outer surface 45 of the bell, and a rod fastened to and disposed within the bell and having a resilient portion terminating in a weight adapted to 50 impact automatically against the inner surface of the bell consequent upon the operation of the hammer; substantially as described.
6. An attachment for a telephone signal 55 box having a gong post mounted on its top, and a vibratory hammer projecting upward through a slot formed in said top adjacent said gong post, said attachment comprising a striker adapted to be secured to the ham- 60 mer, a vertical support adapted to be fas-
- tened to the gong post, and a sounding device suspended vertically from said support and adjustable both horizontally and vertically toward and from the striker to vary the tone emitted when struck thereby; sub- 65 stantially as described.
7. An attachment for a telephone signal box, said attachment comprising a striker adapted to be secured to the usual hammer of the box, a frame adapted to be mounted 70 upon the box and including a vertical member having an inturned lower end for connection to one of the usual gong posts of the box and an elevated cross-piece which overhangs that post, a sounding device for 75 coöperation with the striker suspended axially from the cross-piece, and means whereby the sounding device may be adjusted bodily in a direction transverse to its axis toward and away from the hammer; sub- 80 stantially as described.
8. An attachment for a telephone signal box, said attachment comprising a striker adapted to be secured to the usual hammer of the box, a frame adapted to be mounted 85 upon the box and including a vertical member having an inturned lower end for connection to one of the usual gong posts of the box and a slotted cross-piece which overhangs that post, a depending yoke adjust- 90 ably engaged in the slot in the cross-piece, and a sounding device for coöperation with the striker carried by the yoke and adjustable with the same toward and away from the striker; substantially as described. 95
9. An attachment for a telephone signal box, comprising a striker adapted to be secured to the usual hammer of the box, a vertical support adapted to be fastened to at least one of the usual gong posts of the 100 box, a hollow bell suspended from said support in position to be struck exteriorly by said striker, and an impact member arranged to automatically strike against the interior of said bell consequent upon the 105 operation of the hammer; substantially as described.
10. An attachment for a telephone signal box, comprising a striker adapted to be secured to the usual hammer of the box, a vertical support adapted to be fastened to at 110 least one of the usual gong posts of the box, a hollow bell suspended from said support in position to be struck exteriorly by said striker, and a vibratory impact member arranged to strike against the interior of the bell and set in motion by the vibration of said bell; substantially as described. 115

In testimony whereof I affix my signature.
CHARLES MANNING VAN HEUSEN.
